EDMUND HOXIE, OF SOMERVILLE, MASSACHUSETTS.

FUEL BURNER.

Application filed March 2, 1921. Serial No. 449,051.

To all whom it may concern:

Be it known that EDMUND HOXIE, a citizen of the United States, and resident of Somerville, in the county of Middlesex and 5 State of Massachusetts, has invented new and useful Improvements in Fuel Burners, of which the following is a specification.

This invention relates to devices for use in connection with the burning of liquid 10 or gaseous fuel and more particularly to a carbureting device intended to supply a suitable mixture of such fuel with air or other oxidizing agent under pressure for heating metallurgical or other furnaces, 15 forges, muffles, kilns and in fact any heat generating device wherein liquid or other mobile fuel may be utilized and where a supply of air, steam, or other gaseous fluid under pressure is available.

20 In the use of liquid or gaseous fuel it is highly important from the standpoint of economical use as well as in the attainment of high degrees of temperature that the fuel be mingled with air or other oxidizing 25 medium in sufficient quantity to assure complete combustion. Unless however the fuel is very thoroughly subdivided and reduced to a mist-like form, if not actually gasified, before it is burned, it is impossible 30 to obtain the best results even though the proper quantity of oxygen be supplied, and in many burner devices as at present constructed such thorough breaking up of the fuel and its mixture with air is very 35 imperfectly attained.

One object of the present invention is to provide for the effective admixture of liquid or gaseous fuel with air whereby such fuel may be thoroughly broken up and reduced 40 to a mist-like form or vapor whose particles shall be intermingled with and suspended in a suitable quantity of air to promote complete combustion. As one mode of attaining this object the fuel may be admitted 45 to a stream of air or other gaseous fluid under pressure and such stream with the fuel carried thereby may be permitted to enter an expanding chamber wherein the particles of fuel may be permitted to impinge violent- 50 ly against a suitable baffle or deflector member whereby the droplets of fuel are completely broken up and by reason of the eddies formed in the expansion chamber are thoroughly mixed with such gaseous fluid. 55 In connection with this arrangement, if desired, the fuel may be admitted to the pres-

sure fluid stream by inspirator means comprising a Venturi tube.

In the employment of gaseous fluid under pressure as a means for supplying fuel 60 to a burner, it is undesirable to employ such fluid in sufficient quantity to promote complete combustion of the fuel as the quantity necessary for such purpose is relatively great and makes the use of a burner so supplied 65 with the necessary oxidizing agent unnecessarily expensive.

If the pressure fluid employed be air, the cooling effect of the necessary quantity thereof in expanding from high pressure 70 is undesirable as it tends to lower the temperature of the furnace to a substantial degree. Furthermore, when it is attempted to employ such a large volume of compressed air, difficulty is experienced from 75 the presence of condensed water in the blower pipe. Under some circumstances water may accumulate in sufficient quantity to extinguish the flame in the furnace, and even when in smaller amount such water neces- 80 sarily results in a lowering of the furnace temperature. If steam under pressure be employed as the fuel conveying medium, similarly undesirable results are attained and incomplete combustion of the fuel re- 85 sults. Moreover, in many instances, for example in forges, muffles, etc., it is undesirable to have the mingled air and fuel admitted in a blast of such intensity as results from the direct use of air under the 90 usual pressures employed in industrial es- tablishments.

A further object of the invention is to provide a device whereby a relatively small quantity of a gaseous medium under high 95 pressure may be employed for breaking up the fuel into proper form for burning and if desired for producing an inspiring action in the fuel pipe, while at the same time serving to induce the flow of a relatively large quantity of air at atmospheric pressure and temperature for properly diluting the mingled fuel and high pressure fluid.

To this end the mingled fuel and gaseous 105 fluid under pressure may, after mixing, be delivered from a suitable nozzle into an air inspirator comprising free air inlets and a chamber having converging walls whereby the stream of fuel and pressure fluid serves 110 to induce the flow through such inlets of relatively large volumes of atmospheric air.

While in most cases compressed air would be employed as the fuel conveying medium it is evident that other gaseous fluids such as steam or combustible gas under pressure 5 might be employed. With the present arrangement, if steam is used the relatively small quantity of steam admitted to the furnace is of little consequence so far as its moisture content is concerned while any 10 heat resulting from condensation of the steam is merely transferred to the fuel and air so that no loss of heat takes place.

In the following description, the term "air" has been employed as indicative of a 15 suitable pressure fluid for conveying the particles of fuel, but it is to be understood that air is referred to merely as illustrative of a desirable means for attaining the desired end and that any other fluid medium such as 20 steam under pressure or gas might be employed for the purpose. It is also clear that while primarily intended for use with liquid fuel, the apparatus herein disclosed, might, with little change be used for the feeding 25 of gaseous or even pulverized solid fuel. Moreover while primarily intended as a fuel burner, the device is equally efficacious as a blower whereby, by the use of a relatively small amount of pressure fluid such as 30 compressed air, a large quantity of free or atmospheric air can be induced to flow through the delivery tube. When so employed little or no difficulty is experienced from the presence of small quantities of condensed moisture 35 in the pressure fluid, although such moisture has, in connection with the use of air operated blowers such as heretofore known, been a constant source of annoyance and inefficiency.

40 A preferred arrangement for carrying into effect the above objects is illustrated in the accompanying drawings, in which:—

Fig. 1 is a longitudinal cross section of a device particularly adapted to serve as a 45 burner for use in a rivet heating forge;

Fig. 2 is a transverse cross section on the line 2—2 of Fig. 1;

Fig. 3 is a similar cross section on the line 3—3 of Fig. 1;

50 Fig. 4 is a cross section on the line 4—4 of Fig. 1;

Fig. 5 is a cross section on the line 5—5 of Fig. 1;

55 Fig. 6 is a fragmentary longitudinal cross section to enlarged scale of a portion of the device shown in Fig. 1 and illustrating diagrammatically the path of the fluid passing through the mixing chamber; and

60 Fig. 7 is a longitudinal cross section of a modified element useful in connection with a device such as shown in Fig. 1.

Referring to Fig. 1 a composite casing having suitable passages therein for fuel and air is shown having at 1 a connection to 65 which may be secured the delivery end 2 of a

supply pipe for compressed air. This connection has an internally screw threaded portion as at 3 for engagement with a flange member 4 projecting outwardly from a block 5. Extending longitudinally through the 70 block 5 are a pair of channels or passages 6 through which air under pressure may pass from the pipe 2 to the left-hand side of the block 5. Centrally of the block 5 is formed a chamber 7 which is internally screw 75 threaded at 8 for the reception of a pipe 9, such pipe leading from any suitable source of liquid fuel. Extending laterally from the chamber 7 is a passage 10 which extends through a projection 11 at the left-hand side 80 of the block 5, such projection being of substantially cylindrical form and tapering in diameter at its outer extremity where the passage 10 terminates in a nozzle opening 12.

The block 5 is provided at its left-hand end with an outstanding flange 13 internally screw threaded for engagement with a nipple 14 extending outwardly from a support 15. The space 16 within the nipple 14 forms a chamber into which the air is delivered 90 from the passages 6, the left-hand wall of such chamber being formed by the end of a plug 17 seated in a suitable bore in the support 15. The block 17 has a longitudinal passage 18 which at its right-hand portion 95 is of substantially conical form and into which projects the nozzle end of the member 11. At its left-hand portion the member 17 is provided with an extension 19 having therein a cylindrical bore 20 forming a continuation of the passage 18, such bore terminating in a delivery opening or nozzle at 21.

The extension 19 is preferably externally screw threaded, and engaging with such screw threaded portion is a sleeve member 22, such sleeve member being arranged to provide a chamber 23 at the left hand end of the extension member 19. The left-hand wall of the chamber 23 comprises a substantially conical surface at 24, the apex of which 110 is directed toward the opening 21. From the base of such conical surface extend a plurality of diverging passages 25 suitably spaced apart, and together constituting a discharge nozzle.

115 The support 15 has extending therefrom a series of spider arms 15^a, 15^b, etc., such arms being connected at their outer extremities by means of a ring member 26, and forming between them air inlet spaces as 27. 120 The ring member 26 is screw threaded as at 28 for the reception of a casing 29, the inner walls of which are of converging form as indicated at 30, such walls merging into a substantially cylindrical portion 31 open at 125 its end as at 32. Such cylindrical portion may, if desired, form the burner or may be connected in any suitable manner to a pipe leading to a burner.

130 In the normal operation of the device as

described, air under high pressure is admitted through the pipe 2 and flowing through the passages 6 is admitted to the chamber 16. At the same time liquid fuel 5 is caused to flow by gravity or in other suitable manner into the chamber 7 and thence out through the nozzle opening at 12 into the conical passage 18. In this passage it is picked up by the rapidly flowing stream 10 of air and carried through the passage 20 where it is discharged at the opening 21 into the chamber 23. As the stream of air and fuel emerges into the enlarged space 23, it is caused to impinge with great violence 15 upon the opposite wall of the chamber as indicated diagrammatically in Fig. 6. Any droplets of fuel of substantial size which may be carried by the air stream are thus broken up into extremely fine particles 20 and as the sudden change of direction of the fluid in the chamber 23 results in the formation of eddies therein such as indicated at A, B, such particles are thoroughly mixed with the stream of air. The mixture 25 then escapes through the passages 25 in a series of divergent streams such as C, Fig. 6, the provision of a large number of the passages 25, which collectively have a cross sectional area substantially larger than that 30 of passage 27, serving to prevent the building up of pressure in the chamber 23 to a point sufficient to interfere with the proper operation of the device. The various streams of mingled air and fuel 35 passing out under high velocity through the openings 25 impinge upon the inclined walls 30 of the casing 29 whereby their direction of movement is changed and at the same time a strong induction action is set 40 up which serves to cause relatively large volumes of air to enter the openings 27. As the fuel has already been very finely divided and intermingled with the air under high pressure and as such mingled air and 45 fuel is discharged from a series of openings 25, it is evident that a very complete mixture of the fuel with the entire mass of air passing through the casing 29 is secured. Thus a very perfect combustion of the fuel 50 is obtained while at the same time but a relatively small quantity of high pressure air is employed. Furthermore by reason of the thorough mixing of the high pressure air and fuel with a large quantity of free 55 air, little, if any, water is condensed from the compressed air thus eliminating a frequent source of trouble encountered in the operation of many prior devices.

In the device shown in Fig. 7, a block 40 60 is illustrated, such block being intended for use in place of the block 5 illustrated in Fig. 1. The block 40 is provided with a converging passage 43 having an extension 44 leading through the nipple 45 and terminating 65 in a discharge nozzle opening. The

left-hand side of the block 40 may be provided with an internally screw threaded flange 46 for engagement with a part such as the member 14 of the support 15 as previously described. The block 40 may also 70 have at its right-hand portion an extension 41 externally screw threaded for attachment to a connection such as the part 1 of Fig. 1 to which may be attached a supply pipe. At its upper portion the block 40 is 75 also provided with a chamber 47 internally screw threaded for the reception of a fuel supply pipe such as 9^a. From the chamber 47 a passage 48 leads directly into the side of the passage 44.

With the arrangement just described, air from the supply pipe is caused to flow through the convergent passage or Venturi tube 43 and with great velocity through the passage 44. This results in a powerful inspirator action which serves to cause an induction of liquid fuel through the passage 48 and the mingling thereof with the stream of air. With this arrangement it is contemplated that it will not be necessary to 85 employ a fuel supply pump or to locate the fuel supply above the apparatus herein described as the induction action produced would serve to elevate the fuel to a considerable height from any suitable supply tank. 90

When employed as a blower only it is merely necessary to discontinue the feed of fuel through the pipe 9, but in such case, if desired, the pipe 9 with the block 5 may be detached from the support 15 and the air 100 supply connection 1 attached directly to the member 14. As thus arranged the air entering chamber 23 through passage 20 is subjected to a whirling motion as above described which so thoroughly agitates it 105 that any particles of condensed moisture are vaporized and reabsorbed, thus eliminating one of the most serious sources of trouble heretofore experienced in connection with blowers of this type. 110

While a preferred form of the invention has here been disclosed it is evident that various changes and modifications of the structure illustrated might be made in accordance with the requirements of any particular use or employment of the device 115 without in any manner departing from the spirit of the present invention.

I claim:

1. A device for use in the burning of liquid fuel, comprising a casing having a mixing chamber therein, means for delivering mingled pressure fluid and liquid fuel into said chamber, a discharge passage leading from said chamber and constituting a nozzle having a plurality of divergent channels, and an open-ended casing arranged co-axially with said nozzle, said casing comprising a conical portion into the larger end whereof said nozzle projects for a substantial dis- 120
- 125
- 130

tance, and a cylindrical burner portion extending from the smaller end of the conical portion.

2. A device of the class described comprising means having a passage for a stream of gaseous fluid, means for admitting fuel to said stream, means for securing a thorough mixture of such fuel with the fluid, a discharge nozzle having diverging openings for such mingled fluid and fuel, and an open-ended casing comprising a portion of conical form merging into a portion of substantially cylindrical form, such discharge nozzle being constructed and arranged to deliver the mingled fluid and fuel into said casing at a point in the conical portion thereof substantially removed from the larger end of such portion.

3. A carbureting device having a passage for gaseous fluid, means for admitting liquid fuel to the passage at a point such that the moving stream of fluid serves to induce the inward flow of fuel, a mixing chamber for the reception of fluid and fuel, a nozzle for delivering mingled fluid and fuel from said chamber, and an air inspirator casing of conical form merging into a cylindrical burner portion, said nozzle being constructed and arranged to deliver into the conical portion of the casing and at a substantial distance from the base thereof.

4. An inspirator device having a funnel-like passage provided with air inlet openings at the larger end thereof, an injector nozzle arranged centrally thereof for inducing the flow of air therethrough, the discharge end of said nozzle being located at a point intermediate the length of said funnel-like passage, a member having therein a mixing chamber and a passage leading therefrom to said injector nozzle, and means for discharging a stream of mingled gaseous fluid and liquid fuel under pressure into said chamber.

5. A fuel burner comprising a casing having a passage therein, a nozzle for the delivering of gaseous fluid under pressure into said passage, means for admitting fuel to said passage for mixture with fluid under pressure, a chamber in said casing forming a continuation of said passage, the wall of said chamber opposite the opening of said passage being inclined to the axis of said passage, a nozzle for delivering mingled fluid and fuel from said chamber, and an air inspirator casing comprising a portion having converging walls and a cylindrical burner portion in continuation thereof, said nozzle projecting for a substantial distance into the conical portion of said casing.

6. A burner comprising a pressure fluid actuated fuel inspirator device, means providing a passage leading from said device and a chamber forming a continuation thereof, baffle means for opposing the direct passage of fluid through the chamber, discharge

passages leading from said chamber and constituting a nozzle, and a free air inspirator casing enclosing said nozzle, said inspirator casing having a conical portion, and means providing for the admission of air into the base of said conical portion, the nozzle being disposed centrally of said openings and projecting inwardly from said base.

7. A fuel burner comprising a member providing a passage for fluid under pressure, said passage having a portion of enlarged diameter, an impact member within said enlarged portion for impingement by the stream of fluid whereby to produce eddies therein, a nozzle for delivering the fluid discharged from said enlarged portion of said passage, and means providing a chamber of conical form having air openings in its base, said nozzle discharging at a point removed from said base and delivering the fluid discharged toward the apex of said chamber.

8. A burner for liquid fluid comprising a casing having conically converging walls, means providing for the admission of air into the larger end of the casing, a nozzle for delivering mingled air and liquid fluid under pressure in divergent streams into said casing, said nozzle projecting into said casing at the larger end thereof, and being so disposed as to deliver said streams divergently toward the apex of the casing, a member extending from said casing and providing a passage leading to said nozzle, and an impact member in said passage upon which the fluid passing therethrough impinges whereby to secure homogeneity thereof.

9. A burner of the class described comprising a casing having a portion of substantially conical form, means providing for the admission of air into the larger end of said casing, a nozzle arranged centrally of said base for discharging gaseous fluid under pressure into said casing, said nozzle projecting for a substantial distance into said casing and being constructed and arranged to direct fluid discharged therefrom in the direction of the apex of said casing, and means interposed between said nozzle and the source of such fluid for insuring agitation thereof.

10. A fuel burner comprising a substantially cylindrical nozzle tube having a series of divergent discharge openings, a casing enclosing said nozzle tube, means providing for the admission of air at spaced points surrounding the base of such tube, said casing having inner walls which converge toward a point opposite the end of such nozzle tube whereby fluid discharged from the latter is caused to impinge upon said walls, means for delivering air under pressure to said nozzle, and a chamber interposed between said nozzle and the source of such air.

under pressure and from which chamber said nozzle openings diverge.

11. An injector device comprising a casing having a funnel-like passage, an open spider for supporting said casing at one end, a cylindrical injector nozzle arranged centrally of the casing and projecting for a substantial distance axially of said passage, a member having therein an agitating chamber and a passage leading therefrom to said injector nozzle, and means for discharging a stream of gaseous fluid into said chamber.

12. A fuel burner comprising a cylindrical block having a lateral opening and an axial discharge passage, means for in-

ducing the flow of fuel through said opening and passage, a casing having screw-threaded engagement with said block, said casing having an open spider at its free end, a tubular structure fixed to said spider, and 20 providing a conical chamber merging into a cylindrical passage having an open end, and a casing secured axially within said first casing and having a fuel mixing chamber in continuation of the axial discharge 25 opening in said block.

Signed by me at Boston, Massachusetts, this twenty-sixth day of February, 1921.

EDMUND HOXIE.
